UNITED STATES PATENT OFFICE

FREDERICK PURDY, OF FLINT, MICHIGAN, ASSIGNOR TO MARVEL CARBURETER COMPANY, OF FLINT, MICHIGAN, A CORPORATION OF ILLINOIS

CARBURETOR HEAT CONTROL

Application filed June 24, 1929. Serial No. 373,220.

This invention relates to means for controlling the heat supplied to the carburetted mixture during its passage to the cylinders of an internal combustion engine.

5 One of the objects of this invention is to provide an improved and simplified heat control for the explosive charge or carburetted mixture.

The present invention relates to a simplified and improved induction system wherein an enlarged portion of the conduit has a part of its perimeter heated while another portion is relatively cold, and in which a displacing body of low heat conductivity may be interposed between the flowing stream of mixture and various parts of the walls of the conduit so that the stream may be subjected to a variety of temperatures coincidentally with various positions of the carburetor throttle.

20 Another object of this invention is to provide a combined exhaust manifold and intake passage wherein a portion of the periphery of the intake passage is exposed to the exhaust gases, and to provide diversion means within 25 said intake passage for varying the path of mixture flow relative to the heated portion of said passage.

Another object of this invention is to provide a combined exhaust manifold and intake passage wherein a portion of the periphery of the intake passage is exposed to the exhaust gases, and to provide diversion means within 30 said intake passage for varying the path of mixture flow relative to the heated portion of said passage.

A further object of this invention is to provide a simplified and improved heat control of the type described that can be economically manufactured and will be reliable in 35 service.

Other and further important objects of this invention will be apparent from the disclosures in the specification and the accompanying drawings.

This invention (in a preferred form) is illustrated in the drawings and hereinafter more fully described.

On the drawings:

50 Figure 1 is a side elevation of an engine

manifolding system embodying the features of this invention.

Figure 2 is a section on the line II—II of Figure 1.

Figure 3 is a section on the line III—III 55 of Figure 2.

As shown on the drawings:

A manifolding system for internal combustion engines is shown in Figure 1 wherein an exhaust manifold, designated generally 60 by the reference numeral 10, collects the exhaust gases through four branches 11 leading to ports in the cylinder block, which is not shown in the drawings. In this particular manifolding system no manifold as such is 65 shown for the intake or carburetion system, the distribution being taken care of by passages in the cylinder block. The carburetion system comprises a carburetor 12 having a throttle valve 13 on a shaft 14 and a mounting flange 15 attached to a similar flange 16 on an elbow fitting 17 which in turn is secured at the inlet to a cross passage 18 beneath and formed integral with the exhaust manifold 10 between the inner branches 11. 70 This passage is formed of an area approximately double the carburetor outlet area and terminates in a restricted outlet flange 19, of approximately the area of the carburetor outlet, which flange is adapted to be attached 75 to the engine cylinder block at the inlet to the mixture distributing passages therein.

The cross passage 18, while integral with the exhaust manifold, has the lower half 20 of its wall formed as an external surface 85 which in consequence is not directly heated by the exhaust gases; while the upper half 21 of the wall forms an integral hot spot with exhaust gases on one side. In order to distribute the exhaust heat over the upper half 21 the exhaust manifold is specially contoured to form a widened relatively shallow passage 22 above the top wall 21 and is provided with pockets 23 extending part way down the sides of the intake passage. Thus 90 the upper half of the passage 18 is subjected to the direct heat of the exhaust gases from half the engine cylinders when the carburetor is symmetrically disposed. More or less heat 95 may be obtained by shifting the carburetor 100

location towards or away from the outlet end of the exhaust manifold.

With this heating arrangement, if some means is provided for deflecting the incoming fuel and air mixture into the top or bottom half of the enlarged passage 18, it will be evident that the heating effect on the mixture will be varied between wide limits. One means of accomplishing the desired result

- 6 10 comprises a shaft 24 axially mounted relative to the passage 18 and carrying a diametrically disposed partition 25 having semi-circular end closures 26 and 27 which contact the wall of this passage and the restricted 15 outlet respectively, the whole forming in effect a semicylindrical plug obstructing one-half of the passage. By suitably rotating this plug the mixture may be caused to flow in contact with different portions of the wall 20 of the passage 18 thus providing a full range of heat control.

Broadly, the shaft 24 may be rotated or oscillated in any suitable manner as by a 25 manual control if it is desired to compensate for general operating conditions, such as temperature. Specifically, I have chosen to illustrate a control of the heating effect in proportion to the throttle movement, as it is well known that much less heating is desirable at full throttle than is required to obtain smooth idling at nearly closed throttle. The illustrated control comprises interengaging gear segments 28 and 29 mounted on the throttle shaft and control shaft respectively. 30 If the throttle shaft has a total movement of 60 degrees and a half turn of the control shaft is desired a three to one gear ratio will give the desired movement. Also, if it is desired to vary the proportional movement of the control shaft relative the throttle at different degrees of opening of the latter, segments of elliptical or Geneva gears may be employed to produce the desired result.

45 In the operation of this device, when the plug valve in the passage 18 is in the position shown in Figure 2, corresponding to a full throttle opening, the carburetted mixture flows through the lower half of the passage 18, in contact with the unheated wall 20. The hollow effect of the plug valve serves as a dead air insulating space which materially reduces the transmission of heat to the mixture from the upper heated half of the passage 18, so that in this position of the valve the mixture is relatively unheated, more especially so as the maximum volume of mixture is flowing at high speed. When the throttle is closed for idling the interconnected control shaft is rotated substantially 180 degrees by the throttle movement, thus positioning the plug valve in the lower half of the passage 18, thus causing the mixture to flow in the upper heated portion of the passage in contact with the wall 21. As the mixture flow is at a minimum during idling, the

heating effect thereon will be augmented by the slow travel of the mixture through the heating zone. At intermediate positions of the control shaft and plug valve the heating effect will be varied in proportion to the relative exposed areas of the heated and unheated walls of the passage 18.

75 It will thus be seen that I have provided an improved and simplified variable heating control for the carburetted mixture supplied to internal combustion engines, which control does not depend upon the throttling or control of the heating fluid per se.

I am aware that many changes may be made, and numerous details of construction 80 may be varied through a wide range without departing from the principles of this invention, and I, therefore, do not purpose limiting the patent granted hereon, otherwise than necessitated by the prior art.

85 I claim as my invention:

1. A carburetted system for internal combustion engines including a carburetted device, a tube forming a mixture passage connected to said carburetted device, heating means associated with said tube to heat the same, and means disposed within said tube for causing the mixture flowing therethrough to be moved into and out of contact with the heated portion of the circumference of said tube, said latter means including a pivotal element for bodily moving the path of the mixture flow into and out of a position where said mixture may be acted upon by said heating means.

100 2. A carburetted system for internal combustion engines including a carburetted device, a tube forming a mixture passage connected to said carburetted device, heating means associated with said tube to heat the same, means disposed within said tube for causing the mixture flowing therethrough to be moved into and out of contact with the heated portion of the circumference of said tube, said latter means including a rotatable segmental element occupying a portion of the space within said tube whereby rotation thereof will bodily shift the path of the mixture flow within said tube into and out of a position where said mixture may be acted 105 upon by said heating means.

110 3. A carburetted system for internal combustion engines including a carburetted device, a tube forming a mixture passage connected to said carburetted device, heating means associated with said tube to heat a portion of the circumference thereof, means disposed within said tube for causing the mixture flowing therethrough to be moved into and out of contact with the heated portion of the circumference of said tube, said latter means including a pivotal element for bodily moving the path of the mixture flow into and out of a position where said mixture may be acted upon by said heating means.

4. A carburetting system for internal combustion engines including a carburetting device, a tube forming a mixture passage connected to said carburetting device, heating means associated with said tube to heat a portion of the circumference thereof, means disposed within said tube for causing the mixture flowing therethrough to be moved into and out of contact with the heated portion of the circumference of said tube, said latter means including a rotatable segmental element occupying a portion of the space within said tube whereby rotation thereof will bodily shift the path of the mixture flow within said tube into and out of a position where said mixture may be acted upon by said heating means.

5. In a carburetting system for internal combustion engines, a tube through which the carburetted mixture flows on its way to the engine, heating means associated with the tube, means disposed within said tube for varying the path of the flowing mixture to cause it to be moved into and out of the direct heating zone of said heating means, said latter means including a pivotal element for bodily moving the path of the mixture flow into and out of a position where said mixture may be acted upon by said heating means.

6. In a carburetting system for internal combustion engines, a tube through which the carburetted mixture flows on its way to the engine, heating means associated with the tube for heating a portion of the wall thereof, means disposed within said tube for varying the path of the flowing mixture to cause it to be moved into and out of the direct heating zone of said heating means, said latter means including a pivotal element for bodily moving the path of the mixture flow into and out of a position where said mixture may be acted upon by said heating means.

7. In a carburetting system for internal combustion engines, a tube through which the carburetted mixture flows on its way to the engine, heating means associated with the tube for heating a portion of the wall thereof, means disposed within said tube for varying the path of the flowing mixture to cause it to be moved into and out of the direct heating zone of said heating means, said latter means including a rotatable segmental element occupying a portion of the space within said tube whereby rotation thereof will bodily shift the path of the mixture flow within said tube into and out of a position where said mixture may be acted upon by said heating means.

8. In a carburetting system for internal combustion engines, a tube through which the carburetted mixture flows on its way to the engine, heating means associated with the tube, means disposed within said tube for varying the path of the flowing mixture to

cause it to be moved into and out of the direct heating zone of said heating means, said latter means including a rotatable segmental element occupying a portion of the space within said tube whereby rotation thereof will bodily shift the path of the mixture flow within said tube into and out of a position where said mixture may be acted upon by said heating means.

9. In a carbureting system for an internal combustion engine, an intake tube between the carburetor and the engine, heating means enveloping a sector of said tube, and a rotatable element in said tube defining a mixture passage and locating said passage adjacent any desired portion of said enveloped sector.

10. In a carbureting system for an internal combustion engine, an intake tube between the carburetor and the engine, heating means enveloping a sector of said tube, an element in said tube defining a mixture passage, and means for rotating said element whereby said mixture passage is brought into and out of contiguity with said enveloped sector.

In testimony whereof I have hereunto subscribed my name at Chicago, Cook County, Illinois.

FREDERICK PURDY.
